DESIGN FOR WALL-PAPER.

Design No. 12,506, dated October 4, 1881.

UNITED STATES PATENT OFFICE.

EDUARD LEISSNÈR, OF NEW YORK, N. Y., ASSIGNOR TO LEISSNÈR & LOUIS,
OF SAME PLACE.

DESIGN FOR WALL-PAPER.

SPECIFICATION forming part of Design No. 12,506, dated October 4, 1881.

Application filed August 25, 1881. Term of patent 3½ years.

To all whom it may concern:

Be it known that I, EDUARD LEISSNÈR, of New York city, in the county and State of New York, have invented a new and original Design 5 for Wall-Papers, of which the following is a specification.

This invention relates to a new and original design for wall-paper and similar fabrics; and it consists in the novel grouping and configuration of parts hereinafter more fully described.

The accompanying photograph illustrates a face view of a wall-paper having my new design.

a and *b* are two borders on opposite sides of the paper. Each of them is composed of outer narrow stripes and of an inner broader stripe containing leaflets and conventional flowers, as indicated. Between these borders *a* and *b* is the main body of the paper. The same is 15 ornamented by the two principal groups H and I. The group H clusters around a three-foil-shaped ornament containing a central rosette, and having radiating from its circumference flame-like shoots, between which branches *o* and *h* project from said figure. The group I 20 clusters around a central figure that might be termed "spider-like," having four prominent ovals for the body, three nearly-oval figures in line to represent the head, and three oval figures 25 at the back. Leg-like projections at the sides

and tapering projections in front, indicating the antennæ, extend from these ovals to increase the resemblance. A butterfly-shaped figure appears to fly toward the said spider-shaped figure. Beyond the latter projects a 35 branch, *i*, having leaves thereon, and another branch, *j*, with leaves thereon, and back of it is the crown-shaped figure *r*, the rosette-like figure *t*, and a peculiarly-formed figure, *s*, which is composed of series of ovals with pointed projections thereon, as indicated.

I claim—

1. The design for wall-paper, consisting of the group H and figures *h* and *o*, substantially as shown.
2. The design for wall-paper, consisting of the group I and figures *i* *j* *r* *s* *t*, substantially as shown.
3. The design for wall-paper, consisting of the group H and figures *o* and *h*, the group I 40 and figures *i* *j* *r* *s* *t*, substantially as shown.
4. The design for wall-paper, consisting of the group H and figures *o* and *h*, the group I 45 and figures *i*, *j*, *r*, *s*, and *t*, and the stripes A and B, substantially as shown.

EDUARD LEISSNÈR.
